UNITED STATES PATENT OFFICE.

WILBUR SCHUTTE, OF CHICAGO, ILLINOIS.

ROTARY VALVE FOR INTERNAL-COMBUSTION ENGINES.

1,151,499.

Specification of Letters Patent. Patented Aug. 24, 1915.

Application filed March 25, 1914. Serial No. 827,069.

To all whom it may concern:

Be it known that I, WILBUR SCHUTTE, a citizen of the United States, and a resident of the city of Chicago, county of Cook, and State of Illinois, have invented certain new and useful Improvements in Rotary Valves for Internal-Combustion Engines, of which the following is a specification.

My invention relates to rotary valves for internal combustion engines which are designed for use especially in controlling the intake and exhaust of the explosion chamber of an engine.

The object of my invention is the production of a valve as mentioned which will be of improved construction and efficient in operation.

Other objects will appear hereinafter.

With these objects in view my invention consists in the combinations and arrangements of parts hereinafter described and claimed.

The invention will be best understood by reference to the accompanying drawings forming a part of this specification, and in which—

Figure 1 is a vertical longitudinal section through the upper end portion of an internal combustion engine equipped with a valve embodying my invention, Figs. 2 and 3 are sections taken on lines 2—2 and 3—3 respectively of Fig. 1, Fig. 4 is a top plan view of the construction shown in Fig. 1, Fig. 5 is a view of one end of the construction, Fig. 6 is a view of the opposite end of the construction, Fig. 7 is a top plan view of the upper end portions of the cylinders of the engine with the valve removed, Fig. 8 is a side elevation of the body of the valve detached, and Fig. 9 is an end view of said valve body.

The preferred form of construction as illustrated in the drawings comprises an internal combustion engine consisting as shown in this case of two cylinders 6 which are surrounded by cooling jackets 7 formed in the walls of said cylinders. The upper ends of the explosion chambers which are constituted in said cylinders are closed by a plate 8 which is rigidly secured in position by means of bolts 9 and 9'. The plate 8 is formed with openings 10 which register with the upper ends of cooling jackets 7. Also formed in said plate for co-operation with each of the cylinders 6 are intake and exhaust ports 11 and 12 respectively, there

being two of each which are arranged in transverse alinement as clearly shown in Fig. 7. Said ports are elongated in order to afford intake and exhaust passages of considerable size and in order to permit of the elongation desired the upper ends of the cylinders 6 are also enlarged as clearly shown in the several views.

Mounted upon the plate 8 is a cylindrical housing 13 rigidly secured in position by means of the bolts 9 which pass through laterally projecting flanges formed at the base of said housing as clearly shown in Figs. 2 and 3. Formed in the peripheral wall of said housing is a cooling jacket 14 which communicates through openings 10 in plate 8 with the jacket 7 of the engine cylinders so that with this construction, the cooling chambers 7 and 14 will be in constant communication so as to permit of the circulation of the cooling water from one to the other.

Rotatably mounted in the housing 13 is a valve body consisting of outer and inner tubes 15 and 16 which are spaced apart and rigidly connected so as to form independent concentric chambers 17 and 18, the former being formed between said tubes 15 and 16 and the latter of said chambers within the tube 16.

Leading from the chamber 17 are passages 19 formed in the tube 15, there being a plurality of passages 19 spaced in said tube for registration with passages 20 formed in the housing 13 which communicate with the intake ports 11 of each cylinder 6 as clearly shown in Fig. 3. The passages 19 co-operating with each cylinder are arranged in circumferential alinement so that upon rotation of the valve body, said passages will successively register with the passages 20 and thus intermittently establish communication between the chamber 17 and the explosion chamber of the corresponding cylinder. Also the passages 19 and the adjacent ends of the passages 20 are so spaced that two of the former will simultaneously register with the latter as clearly shown in Fig. 3. With this arrangement where three passages 19 are formed in the tube 15 equally spaced apart therein as shown, the chamber 17 of the valve will be brought into communication three times with the explosion chamber of the corresponding engine cylinder upon each complete rotation of the valve body.

Leading from the tube 16 of the valve body are pipes 21 communicating at their inner ends with the chamber 18, the outer ends of said pipes being positioned for registration with passages 22 which lead to the exhaust ports 12 of the plate 8. Three pipes 24 lead from the chamber 18 for registration with the ports 12 co-operating with each engine cylinder, the outer ends of said pipes being equally spaced apart in the periphery of the valve body and the adjacent ends of the passages 22 being so arranged that two passages 21 will communicate simultaneously with said passages 22, as clearly shown in Fig. 2, the arrangement being identical with that of the passages 19 relative to the passages 20 above described. Hence with this arrangement it will be seen that exhaust or scavenging of each cylinder of the engine will take place three times upon each complete rotation of the valve, the arrangement of the ports in the valve body being of course such that the periods of intake and exhaust will alternate.

In order to prevent leakage of the gases from the passages 19 to the passages 21 or vice versa, packing rings 23 are employed which are arranged in circumferential grooves 24 formed in the periphery of the valve body between said passages as clearly shown in Fig. 8.

The fuel supply pipe 25 leading from the carburetor 26 communicates with the chamber 17 of the valve body through openings 27 formed in the tube 15 of the valve body, there being a plurality of said openings 27 spaced close together in circumferential alignment so that in the operation of the valve the fuel supply pipe 25 will be in constant communication with said chamber 17.

Cooling of the tube 16 of the valve body is effected through the medium of a cooling jacket 28 which is formed in the walls of said tube as clearly shown in the several views. One end of said jacket communicates through a plurality of passages 29 formed in the head 30 of the valve housing with the corresponding end of the cooling jacket 14 of said housing, the inner ends of said passages 29 registering with spaced perforations 29' formed in the outer wall of said cooling jacket 28, and the outer ends of said passages communicating with openings 29" formed in the corresponding end wall of the jacket 14. The pipes 21 leading from the chamber 18 are also surrounded with cooling jackets 28' which communicate at their inner ends with the jacket 28 as clearly shown in Figs. 1 and 2.

The head 30 of the housing 13 is secured in position by bolts 31, and mounted in said head is a screw plug 32 which serves to close the adjacent end of the passage 18, suitable packing being employed at this point in order to insure a tight connection. The plug 32 is formed with an extension 32' which extends into the chamber 18 a considerable distance in order to serve as a bearing for the tube 16 as will be readily understood. The head 30 serves, as will be readily understood, as a means of locking the valve body against longitudinal movement in one direction, longitudinal movement of said valve body in the opposite direction being prevented by a head 33 secured to the opposite end of said housing by bolts 34. Extending from the head 33 is a pipe 35 which communicates at its inner end with openings 35' spaced at frequent intervals in the adjacent end of the outer wall of the jacket 28 as clearly shown in Fig. 1.

With the construction set forth it will be seen that the cooling jackets 7, 14 and 28 are connected together so that a constant circulation of water therethrough may be maintained when the engine is in operation, it being clear that cold water introduced into the jacket 7 will flow therefrom into the jacket 14 through the openings 10 in plate 8. From said jacket 14 the water will flow through openings 29", passages 29 and openings 29' into the jacket 28, whence the water will be withdrawn through openings 35' into drain or waste pipe 35.

Rotation of the valve body is effected by means of a gear 36 which is rotatably mounted in a housing 37 secured in position at one end of the housing 14 by the bolts 34, said gear snugly fitting said housing so as to be retained thereby in fixed relation with the valve housing. Said gear is connected with the valve body by means of pins 39 formed at one end of the latter which extend longitudinally of said valve body for engagement with recesses 40 formed in the adjacent side of the gear 36. With this arrangement it will be seen that a releasable connection between the valve body and said gear is effected, the arrangement being such that when it is desired to remove the valve body from the housing 13, it is only required to remove the head 30 in which event the valve body may be slid longitudinally from position in said housing, the pins 39 engaging the recesses 40 in such a manner as to permit of this disengagement. Conversely in reinserting the valve body the same will automatically be operatively connected with the gear 36 when said body is properly positioned in the housing 13, since with said valve body so positioned, the pins 39 will be in engagement with the recesses 40. The gear 36 meshes with a pinion 41 fixed to a shaft 42 which is operatively connected through gearing (not shown) with the crank shaft of the engine or other driving element for effecting rotation of the valve body at a speed properly timed with the reciprocations of the pistons of the engine cylinders.

At the upper side of the valve housing are oil cups 43 which register at their inner ends with longitudinally extending grooves 44 formed at the inner side of said housing, said grooves in operation being adapted to register with longitudinally extending grooves 45 formed in the periphery of the valve body in order to lubricate the same.

With the construction set forth then it will be seen that in the operation of the valve the engine cylinders will be supplied with fuel from the chamber 17 to which fuel is supplied by the supply pipe 25 leading from the carburetor, and exhaust will take place into the chamber 18 one end of which will discharge into the outside atmosphere through a muffler which may be employed as is usual. The passages leading from the chambers 17 and 18 will be so spaced that the explosions of the engine cylinders will alternate or, where more than two cylinders are employed, so that the cylinders will operate in proper succession.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. The combination in an internal combustion engine, of an explosion chamber; a cylindrical housing; intake and exhaust ports leading from said chamber to the interior of said housing; a hollow cylinder rotatably mounted in said housing; two independent concentric chambers formed in said cylinder; a plurality of spaced passages extending from each of said chambers terminating in the periphery of said cylinder, the passages communicating with each of said chambers being positioned in circumferential alinement for successive registration with one of said ports; and intake and exhaust pipes communicating respectively with said chambers, substantially as described.

2. The combination in an internal combustion engine, of an explosion chamber; a housing; a plurality of intake ports and a plurality of exhaust ports leading from said chamber to the interior of said housing; a hollow cylinder rotatably mounted in said housing; two independent concentric chambers formed in said cylinder; a plurality of spaced passages extending from each of said chambers terminating in the periphery of said cylinder, the passages communicating with each of said chambers being posi-

tioned in circumferential alinement for successive registration with said intake and exhaust ports, said passages and ports being correspondingly spaced whereby the former will simultaneously register with a plurality of the latter; and intake and exhaust pipes communicating respectively with said chambers, substantially as described.

3. The combination in an internal combustion engine, of an explosion chamber; a cylindrical housing; ports leading from said chamber to said housing; a valve rotatably mounted in said housing, the body of said valve comprising inner and outer concentrically arranged tubes fixed together to form two independent concentric chambers within said valve body; spaced passages in said outer tube leading from said outer chamber for successive registration with one of said ports, when said valve body is rotated; spaced pipes leading from said inner chamber, the inner ends of said pipes being secured in said inner tube, the outer ends of said pipes being positioned for successive registration with the other of said ports; and intake and exhaust pipes communicating respectively with said chambers, substantially as described.

4. The combination in an internal combustion engine, of an explosion chamber; a cylindrical housing; ports leading from said chamber to said housing; a valve rotatably mounted in said housing, the body of said valve comprising inner and outer concentrically arranged tubes fixed together to form two independent concentric chambers within said valve body; spaced passages in said outer tube leading from said outer chamber for successive registration with one of said ports, when said valve body is rotated; spaced pipes leading from said inner chamber, the inner ends of said pipes being secured in said inner tube, the outer ends of said pipes being positioned for successive registration with the other of said ports; and intake and exhaust pipes communicating respectively with said chambers; and a cooling jacket formed in said inner tube, substantially as described.

5. The combination in an internal combustion engine, of an explosion chamber; a cylindrical housing; ports leading from said chamber to said housing; a valve rotatably mounted in said housing, the body of said valve comprising inner and outer concentrically arranged tubes fixed together to form two independent concentric chambers within said valve body; spaced passages in said outer tube leading from said outer chamber for successive registration with one of said ports, when said valve body is rotated; spaced pipes leading from said inner chamber, the inner ends of said pipes being secured in said inner tube, the outer ends of said pipes being positioned 130

for successive registration with the other of said ports; intake and exhaust pipes communicating respectively with said chambers; a cooling jacket formed in said inner tube; inlet and outlet passages for the cooling liquid registering with opposite ends of said inner tube; and a plurality of spaced openings in said ends of said pipe establishing communication between said cooling jacket and said passages, substantially as described.

6. The combination in an internal combustion engine; of an explosion chamber; a cylindrical housing; ports leading from said chamber to said housing; a hollow cylinder rotatably mounted in said housing; a cylindrical partition concentrically fixed in said cylinder dividing the interior of said

cylinder into two concentric independent chambers; passages extending from said chambers terminating in the periphery of said cylinder, said passages being positioned for intermittent registration with said ports upon rotation of said cylinder; intake and exhaust ports communicating respectively with said chambers; and cooling jackets formed in said housing and said partition in constant communication with each other, substantially as described.

In testimony whereof I have signed my name to this specification in the presence of two subscribing witnesses.

WILBUR SCHUTTE.
